UNITED STATES PATENT OFFICE.

IRVING E. COMINS, OF WORCESTER, MASSACHUSETTS.

DEVICE FOR HOLDING CYLINDERS WHILE ATTACHING CARD-CLOTHING THERETO.

SPECIFICATION forming part of Letters Patent No. 404,685, dated June 4, 1889.

Application filed May 19, 1888. Serial No. 274,444. (No model.)

To all whom it may concern:

Be it known that I, IRVING E. COMINS, of Worcester, in the county of Worcester and State of Massachusetts, have invented a new and useful Improvement in Devices for Holding Cylinders while Attaching Card-Clothing thereto, of which the following, taken in connection with the accompanying drawings, is a specification.

10 My invention relates to card-cylinder holders.

The object of my invention is to prevent the main cylinder of a carding-machine from turning or rotating in the direction in which 15 the card-clothing is being stretched upon the main cylinder during the operation of clothing the said cylinder, and it also permits the main cylinder to rotate freely in the opposite direction when desired.

20 My invention consists, generally, in a holding mechanism for the shaft of the main cylinder of a carding-machine, which will allow the same to revolve in one direction, while the holding mechanism prevents it and the 25 cylinder from revolving in the opposite direction, all as more particularly hereinafter described, and as specified in the claims. The card-clothing has to be renewed frequently, and when put upon the main cylinder has to 30 be stretched the most possible. It is desirable, therefore, to have an attachment for the carding-machine which will hold the main cylinder perfectly rigid, so that it may not move in the direction that the clothing is 35 stretched, but may move freely in the opposite direction, in order that when one sheet of clothing is completely nailed in its place the main cylinder may be revolved to the proper position for commencing the attachment of 40 the next sheet.

In the accompanying drawings, Figure 1 is a perspective view of the main cylinder end of a carding-machine having my improved card-cylinder holder attached to the main-cylinder shaft. Fig. 2 is a plan view of the cylinder-holder. Fig. 3 is a side elevation of the same. Fig. 4 is a longitudinal section through the line $x-x$ of Fig. 2. Fig. 5 is a longitudinal section through the line $y-y$ in 45 Fig. 3. Fig. 6 is a modification.

1 is a sleeve, (see Figs. 2 and 5,) which is adapted to encircle the shaft 16 of the main

cylinder. Surrounding the sleeve 1 is a ratchet-collar 4, Fig. 2. This collar may be cast upon the sleeve or fastened to it in any appropriate manner. Loosely surrounding the sleeve 1 on either side of the ratchet 4 are two rings 20 20, and attached to each of said rings 20 20 is a bar 2.

77 are set-screws, (see Fig. 2,) which, passing through the sleeve 1 outside of the rings 20 20, are adapted to secure the sleeve firmly to the cylinder-shaft 16. It is desirable that the ends of the set-screws which engage with the shaft should be concave, as this greatly increases their holding capacity. If the set-screws do not sufficiently hold the sleeve 1 to the shaft 16, a slight portion of the shaft may be flattened and the screws set up upon this flat surface.

10 and 11, Fig. 2, are bolts, which are adapted to hold the rings 20 20 in place, together with the bars 2 2. Inclosed between the two bars 2 2, and preferably pivoted by the bolt 10, is a pawl 3, (see Figs. 2 and 4,) adapted to engage with the ratchet 4. The bars 2 2 and rings 20 20 serve as a movable support for said pawl. Extending from the back of this pawl is a shoulder 19. (See Fig. 3.) 6 is a flat or bow spring secured to one of the bars 2 2 and adapted to bear against the said shoulder, so as to retain the pawl 3 in engagement with the ratchet.

9 is a handle, preferably of steel, secured to the pawl 3, (see Fig. 3,) and is adapted for 85 disengaging the pawl 3 from the ratchet 4.

18 is a rod, which is pivoted to the bars 2 2 near their outer ends by the bolt 11, the lower end of said rod being adapted to rest upon the floor. This rod 18 is adapted to 90 support the bars 2 2 and the pawl 3, and to serve as a brace to prevent said bars 2 2, pawl 3, ratchet 4, sleeve 1, and shaft 16, to which said sleeve 1 is secured, from rotating in the direction indicated by the arrow a in Fig. 1. 95

In Fig. 6 the periphery of the collar 4 is simply roughened instead of having regular teeth, and in place of the ordinary pawl, as shown in Figs. 1, 2, and 4, an eccentric with a roughened periphery is shown. This is to 100 allow it to impinge upon the face of the collar 4, Fig. 6, and hold the sleeve 1 and shaft 16 at any desirable point. This form of construction has this advantage over the one

illustrated in Figs. 2, 3, and 4, that the main cylinder can be moved short distances so long as they are appreciable. In the case of the ratchet, however, it is necessary to move 5 the cylinder a space represented by the distance between the ratchet-teeth.

The operation of my improved cylinder-holder is as follows: In all carding-machines the shaft of the main cylinder projects beyond the bearings, and upon this extension of the shaft (see 16 in Fig. 1) the sleeve 1 is slipped, and when the attachment is in practically the position indicated in Fig. 1, with the end of the rod 18 resting upon the floor, 10 the sleeve 1 is secured firmly to the shaft 16 by the set-screws 7 7. In this position the shaft and main cylinder and sleeve are free 15 to revolve in the direction indicated by the arrow *b* in Fig. 1, as the teeth of the ratchet 20 4 slip by the pawl 3.

In Fig. 1, *A* represents the main cylinder, and *c* several pieces or sheets of the clothing stretched upon its periphery, while *c'* represents a piece or sheet of the clothing which 25 is about to be stretched, having been securely tacked longitudinally along the line *l*.

The stretching-pinchers 17 nip the lower edge *k* of the clothing and pull it in the direction of the arrow *a*. This pulling or stretching 30 tends to turn or rotate the cylinder in a similar direction. To avoid this difficulty is the object of my invention, and it is accomplished in the following manner: The sleeve 1 and ratchet 4 being secured to the shaft 16, 35 Fig. 1, of the main cylinder, it cannot rotate in the direction of the arrow *a*, as the ratchet 4 will be locked by the pawl 3, which is held firmly in position by its supporting-bars 2 and the brace 18, which rests upon the floor. 40 By bearing down upon the handle 9 the pawl 3 would be disengaged from the ratchet 4, and the cylinder *A* may be revolved in the direction of the arrow *a*, if desired.

Having fully described my invention, I 45 claim—

1. A card-cylinder holder consisting of a sleeve for attachment to the shaft of the main cylinder, a collar having a roughened periphery secured to said sleeve, a retaining device

for engagement with said collar, a movable support for said retaining device, and means for sustaining said support, all substantially as shown and described.

2. A card-cylinder holder consisting of a sleeve with a collar having a toothed or ratchet periphery attached to said sleeve, a pawl for engagement with said ratchet, a movable support for said pawl, and means for sustaining said support, all substantially as shown and described.

3. A card-cylinder holder consisting of a sleeve for attachment to the shaft of the main cylinder, a collar having a roughened periphery secured to said sleeve, a retaining device for engagement with said collar, a movable support for said retaining device, means for sustaining said support, and a bar for releasing the retaining device from engagement with the collar, all substantially as shown and described.

4. The combination of the sleeve 1, having a collar with a roughened periphery attached thereto, the bars 2, having the rings 20, a retaining device for engagement with said collar, and a support for said bars and retaining device, all substantially as shown and described.

5. The combination of the sleeve 1, having a collar with a roughened periphery attached thereto, the bars 2, having the rings 20, a retaining device for engagement with said collar, a support for said bars and retaining device, and the bar 9, all substantially as shown and described.

6. The combination of the sleeve 1, having a collar with a roughened periphery attached thereto, the bars 2, having the rings 20, a retaining device for engagement with said collar, and the brace 18, all substantially as shown and described.

In testimony whereof I have signed my name to this specification, in the presence of two subscribing witnesses, on this 20th day of April, A. D. 1888.

IRVING E. COMINS.
